ARIN G. SEBERG AND HAROLD M. SEBERG, OF RACINE, WISCONSIN

OARLOCK

Application filed September 11, 1929. Serial No. 391,888.

This invention relates to an improvement in boats and more particularly to an oar lock.

It is an object of the invention to provide a roller bearing oar lock that facilitates the rowing of a boat, while constructed of a minimum number of parts.

It is a further object of the invention to provide an oar lock that can be converted to use for sculling a boat.

It is a further object of the invention to provide an oar lock so constructed that on the pull stroke of the oar, a roller bearing is caused to engage one side of the device and on the push stroke engaging the opposite side.

A full and complete understanding of the invention may be obtained from a consideration of the following detailed description taken in connection with the accompanying drawing forming a part of this specification, in which:

Figure 1 is a perspective view of our new and improved oar lock attached to the gunwale of a boat and showing the oar in position,

Figure 2 is a view partly in cross-section taken on the line 2-2 of Figure 1, and

Figure 3 is a view partly in section taken on line 3-3 of Figure 2.

In Fig. 1 of the drawing there is shown a portion 1 of the gunwale of an ordinary row boat to which my new and improved oar lock is attached by means of an angle-iron plate 2 and screws 3.

The plate 2 has a raised or struck-up portion 4 having an opening through which projects a vertical pin 5 having a roller 6 thereon. The pin 5 which tapers slightly upwardly for a portion of its length, is provided near its upper end with an annular groove defining a pair of shoulders 7, between which an antifriction roller 6 is rotatably mounted on the said pin.

My clamp for securing the oar 8 and yet allowing for the up and down and back and forward motion of the oar is composed of a semicircular upper sleeve member 9 and a 50 semicircular lower sleeve member 10 each

having a flange 11 against which the collar of the oar abuts.

The sleeve member 10 has a lower extension portion 12 which is substantially V-shaped in cross-section and is adapted to fit over the pin 5 and to ride against and rock on the raised portion 4 of the plate 2. This is best illustrated in Figs. 2 and 3 of the drawing.

For fastening the two sleeves together and yet allowing for adjustment so that the oar can be used for sculling, we provide bolts 13 having wing nuts 14. When the device is to be used for sculling, the wing nuts 14 are loosened and the lock nuts 15 screwed upwardly toward the wing nuts to provide greater space between the sleeve members, to allow the oar to assume a more nearly vertical position which is desirable in sculling.

Thus it will be seen that in the operation of our device for propelling a boat that with the pull stroke of the oar the lower portion of pin 5 and the roller 6 bears against one side of the member 12. This operation is shown in dotted lines in Fig. 2 of the drawing. Then as the oar is lifted out of the water and rotated and pushed forward the extension member 12 will tilt backward on the raised portion 4 and the pin and roller will ride against the opposite side of the member 12. It will also be readily seen that due to the V shape of the member 12, the oar can be raised up or down as well as being rotatable on the pin 5.

From the foregoing it will be seen that we have assembled a device that is simple, cheap to manufacture and easily installed, which will effectually prevent dislodgment of the oar and yet allow for the free and easy movement necessary in rowing.

We claim:

1. An oar lock comprising a sleeve adapted to receive an oar and bear against the collar thereon, said sleeve consisting of substantially semi-circular upper and lower members, means for adjustably connecting said semi-circular members together, an angle-iron plate adapted to be secured to the gunwale of a boat and having a struck-up portion in its upper face, said struck-up

- portion carrying an upwardly projecting pin, the lower sleeve member bearing on said struck-up portion, said pin extending into the lower sleeve member and having a friction roller thereon, said pin and roller adapted to engage the opposite sides of the lower member in the back and forth movements of the oar, and also permit a pivotal movement of the oar.
- 10 2. An oar lock comprising a sleeve adapted to receive an oar, said sleeve consisting of an upper and a lower semi-circular member, means for connecting the upper and lower members together, means for adjusting the members relatively to each other, said lower member having a hollow downwardly projecting V-shaped extension, said extension having an opening in its lower end for receiving a pin, whereby to pivotally support the oar and to permit its back and forth movements.
- 15 3. An oar lock comprising a sleeve adapted to fit on an oar, said sleeve comprising upper and lower semi-circular members, an angle iron plate adapted to be secured on the gunwale of a boat, an upwardly projecting pin secured in the upper web of said plate, a friction roller mounted on said pin, said pin and roller pivotally supporting said lower member and adapted to engage the opposite sides of the lower member to permit rocking motion of the oar.
- 20 4. An oar lock comprising a supporting plate adapted to be secured to the gunwale of a boat, an upwardly projecting pin secured in said plate, an oar holding sleeve including substantially semi-circular upper and lower sleeve members, an integral guide sleeve carried by the lower member for guiding said pin, and adjusting means connecting the upper and lower sleeves, whereby to adjust the opening between said sleeves for varying the pitch of the oar for sculling a boat.
